UNITED STATES PATENT OFFICE.

HARRY PERRY, OF BROOKLYN, NEW YORK, ASSIGNOR TO METROPOLITAN-COLUMBIA MFG. CO., INC., A CORPORATION OF NEW YORK.

DESIGN FOR A BACKPLATE FOR LIGHTING FIXTURES.

Application filed December 19, 1925. Serial No. 15,794. Term of patent 3½ years.

To all whom it may concern:

Be it known that I, HARRY PERRY, a subject of the King of Great Britain, and a resident of Brooklyn, county of Kings, and State of New York, have invented a new, original, and ornamental Design for Back-plates for Lighting Fixtures, of which the following is a specification, reference being had to the accompanying drawing, forming a part thereof.

In these drawings:

the back plate for lighting fixtures, the portion indicated in full line outline in the drawing being ornamented in the same manner as the portion more fully illustrated; and

I claim:

The ornamental design for a backplate for lighting fixtures, substantially as shown and described.

HARRY PERRY.
